PICKER STICK CHECK

Samuel K. Taylor, Cleveland Heights, Ohio

Application April 29, 1947, Serial No. 744,631

18 Claims. (Cl. 139—163)

1

This invention relates to picker stick checks, that is means for checking the motion of the picker stick and with it the loom shuttle as the latter approaches the end of its travel in either direction across the loom. The conventional means for this purpose comprises a leather strap which tends to wear rapidly, must be readjusted at frequent intervals and must be replaced after a comparatively short period of use. The delays caused by these difficulties decrease the productivity of a loom, which is a relatively expensive machine. Furthermore the duty of the checking means varies more or less during normal operation, as by changes in shuttle speed or mass.

An object of the present invention is the provision of a novel check means which shall require no manual adjustment, which shall automatically compensate for differences in inertia of the shuttle and in which wear and replacement on account of wear will be insignificant.

Another object is the provision of a picker stick check which shall automatically maintain the desired checking ability regardless of any factors in the operation of the machine which may tend to vary the load upon the checking means, as for example changes in the mass or speed of the shuttle.

Still another object of the invention is the provision of means for relieving the effect of the checking means on the inboard stroke of the picker stick.

Other objects and features of novelty will appear as I proceed with the description of those embodiments of the invention which, for the purposes of the present application, I have illustrated in the accompanying drawings, in which

Fig. 1 is an elevational view, somewhat diagrammatic in character, of a portion of a lay embodying the invention.

Fig. 2 is an enlarged plan view of the check.

Figs. 3 and 4 are vertical sectional views taken substantially on the lines 3—3 and 4—4 of Fig. 2.

Fig. 5 is a transverse sectional view taken substantially on the line 5—5 of Fig. 2 illustrating especially the ratchets and pawls employed for varying the spacing of the friction plates between which the picker stick moves.

Fig. 6 is a plan view similar to Fig. 2 of a modified form of check, and

Figs. 7 and 8 are vertical sectional views taken respectively on the lines 7—7 and 8—8 of Fig. 6.

In the drawing 10 represents the base of a loom carrying two or more bearings 11 in which a shaft

2

12 is oscillatable. 13 represents one of a plurality of arms fixed upon shaft 12 supporting a track 14 with a guide 15 along which the shuttle 16 travels from one binder box 17 to the other. 5 In order to simplify the illustration one side only of the lay is shown.

One of the picker sticks is illustrated at 18. It is provided with a picker head 19 and is diagrammatically illustrated as provided with a slot 20 at 10 its lower end receiving a pin 21 extending through the shaft 12, whereby the picker head 19 may remain at the level of the binder box as it travels therethrough regardless of the angle of the picker stick. Conventional operating means for 15 driving the picker stick in the inboard direction is indicated by a power strap 23. The return of the picker stick thereafter to its intermediate position shown in full line in Fig. 1 may be effected by suitable spring means diagrammatically indicated at 24 in that figure.

At each end of track 14 there is a bracket means comprising a pair of angles 25 which depend from the track on opposite sides of the plane of movement of the stick. These angles 25 carry downwardly projecting Z-shaped arms 26. In this bracket means there is mounted a rigid housing or frame 27 which carries the assembly of parts making up the picker stick check of this invention.

30 A pair of parallel pivot pins 30 carried by housing 27 extend through bars 31. Sheet metal plates 32 are secured to and extend inwardly from these bars 31. In effect the bars 31 constitute parts of the plates 32, and the term plates 35 as hereinafter employed should be understood to include these bars. The plates 32 are flared apart at their inboard ends in order to guide the picker stick into the space between them as it swings to the left as viewed in the drawing. The 40 plates are adapted to swing upon the pins 30 to a limited extent so that they may present variable degrees of friction to the moving stick, and the latter is provided with an armor in the form of a U-shaped guard 34, the legs of the U being spaced apart somewhat further than the thickness dimension of the picker stick 18. The guard 45 is mounted by means of a single bolt 35 extending through the stick and through that part of the U-shaped guard which joins the legs of the U. By reason of this construction the guard is free to turn to a limited extent upon the bolt 35 and thus to adjust itself to compensate for any slight out-of-parallelism with the plates.

The pins 30 are free to move in cam slots 37 55 formed in the top and bottom members of hous-

ing 27 and in the bracket members 25 and 26 attached thereto. The pins are urged toward the outboard ends of slots 37 by springs 38 above and below the housing, which springs loosely surround the ends of the pins 30 and are secured to the opposite ends of rods or bolts 39 which are fixed in the housing. Because of this construction any movement of the bars 31 and plates 32 in the inboard direction causes pins 30 to move in cam slots 37, thereby spreading the plates 32 apart to a slight extent and relieving friction between the plates and the picker stick during travel of the latter in the inboard direction.

Coil springs 40 disposed between the bars 31 and the side members of housing 27 on the outboard side of pivots 30 tend to swing the outboard ends of bars 31 toward each other and thus to spread the plates 32. Upstanding pivot pins 41 are mounted in the outboard ends of bars 31. These pins 41 are drilled horizontally to receive loosely a transverse rod 42 that may be provided with a knurled head 43 for convenience in assembly. The outer ends of bars 31 are slotted, as indicated at 44 in Figs. 3 and 4, to clear rod 42.

A ratchet 45 surrounds rod 42 and its hub is secured to the rod, as by means of a pin 46. A second ratchet 47 having half the number of teeth of ratchet 45 is threadably mounted on the rod 42. It will be observed that rotation of ratchet 45 in a counterclockwise direction as viewed in the drawing threads the rod 42 into the ratchet 47, thus tending to bring the ratchets together, whereas rotation of ratchet 47 also in a counterclockwise direction causes that ratchet to move away from ratchet 45. The hubs of the ratchets bear against the two bars 31. Therefore as the ratchets move away from each other due to rotation of ratchet 47 the bars 31 are separated, while as the ratchets move toward each other due to rotation of ratchet 45 springs 40 move the bars 31 toward each other.

Ratchet 47 is rotated by means of a spring pawl 50 secured to a plunger 51 which is mounted to slide through a hole in block 52 secured to the bottom of the housing 27. This plunger is biased toward the right, as viewed in the drawing, by a coil spring 53 bearing at one end against block 52 and at the other end against a head 54 on the plunger. In order to make the length of the plunger adjustable, its inboard end is drilled and tapped to receive a screw 55 which may be held against accidental rotation by a lock nut 56. In those instances in which the blow delivered by the shuttle against the picker head 19 causes the stick 18 to slide plunger 51 to the left far enough to engage a tooth of ratchet 47, as indicated in Fig. 4, spring 53 will operate plunger 51 and pawl 50 to rotate the ratchet one tooth in the counterclockwise direction.

A spring pawl 60 for rotating ratchet 45 is fixed at its inboard end to the housing 27. Each time the picker stick 18 is moved in the inboard direction by the power strap 23 its friction against the plates 32 pulls those plates to the right as viewed in the drawing, which advances the ratchets far enough to enable pawl 60 to engage a tooth on ratchet 45. Then as the springs 38 return the plates 32 ratchet 45 is rotated one tooth in the counterclockwise direction.

The movement of the check assembly, made up of the plates 32, bars 31, rod 42 and ratchets 45 and 47, back and forth, is sufficient to impart

rotation to ratchet 45. The pawl 50 however does not move far enough on every pick to engage a tooth of ratchet 47. When it does engage a tooth the rotation of the ratchet is through an angle double that of ratchet 45, since its teeth are double the size of the teeth of the latter ratchet. Whenever the spacing of plates 32 reduces friction sufficiently to enable stick 18 to travel to the left to a predetermined extent the pawl 50 advances ratchet 47 and thereby separating the ratchets and drawing plates 32 together to increase the friction which they exert on the stick. On the next pick, ratchet 45 will be rotated and the grip of plates 32 on the stick will be loosened. Thus the setting of the plates is varied a small increment one way or the other for each pick and an approximately constant friction is maintained against the stick during its travel from intermediate position shown in full lines in Figs. 1, 2 and 3 to its outboard position shown in broken lines at 0 in Fig. 1. Thus the shuttle is checked smoothly and effectively, and defects in the cloth caused by inaccurate checking are eliminated.

In the modification illustrated in Figs. 6, 7 and 8, the various elements are the same for the most part as in the first described form of the invention. The frame 27 is hung upon brackets 25 which are attached to the frame by means of screws 65. The pins 66 upon which the bars 31 are pivoted are mounted in a fixed position in the upper and lower members of the frame 27. The pawl 50 is mounted in precisely the same way as in the first described form, but the pawl 60, instead of being attached to the frame, is mounted upon a second plunger 67 which slides in a bore in the block 52 and is biased toward the right as viewed in the drawing by a coil spring 68 bearing at one end against the block 52 and at the other against the head 69 of the plunger.

In this form of the invention therefore the plates 32 do not have any bodily movement, but merely swing through a minute arc upon their pivots 66. In the inoperative position of the plungers, plunger 67 extends considerably further to the right than the plunger 55, and it is moved to the left on each stroke of the stick far enough to engage one tooth of ratchet 45, so that its return stroke under the influence of spring 68 turns ratchet 45 counterclockwise through an angle corresponding to the angular dimension of a tooth, or one-twenty-fourth ($\frac{1}{24}$) of a revolution in the case illustrated. Rod 42 is therefore turned counterclockwise through the same angle, and by its threaded connection with the hub of ratchet 47 aided by the springs 40 draws that ratchet toward ratchet 45. This results in a slight spreading of the plates 32 and a corresponding decrease of friction between those plates and stick 18. The same reciprocation of stick 18 will move plunger 51 to the left more or less, but such movement may not be sufficient to cause pawl 50 to engage a new tooth on ratchet 47. In the usual operation of the device a new tooth of ratchet 47 will be engaged on every other reciprocation of the stick, and as there are half as many teeth in ratchet 47 as in ratchet 45 the distance between plates 32 will average the same. However if anything occurs during the operation of the machine which tends to affect the operation of the check, so that the degree of friction exerted by the plates 32 needs to be altered in order to maintain the desired checking action, one or the other of the ratchets will be advanced one tooth more than normal, or even a tooth in

each of more than one consecutive strokes, to bring about the necessary friction change.

As a result of the invention the operation of the loom proceeds indefinitely without the occasional work stoppages which must be resorted to in looms provided with conventional checking means in order to make adjustments of the checks.

Having thus described my invention, I claim:

1. In a loom, means for checking outward movement of the picker stick in response to a blow delivered to the picker head by the shuttle, which comprises settable means for engaging the picker stick and dampening its outward travel, the checking effect of said means being due to frictional action, and automatic means responsive to the degree of checking effect exerted upon the picker stick during its outward travel for varying the setting of said dampening means upon the inward travel of the picker stick.

2. In a loom, means for checking outward movement of the picker stick in response to a blow delivered to the picker head by the shuttle, which comprises a pair of plates between which the stick travels and by which its motion may be dampened frictionally, and automatic means responsive to the friction exerted by said plates upon the moving stick for varying the spacing of said plates to maintain the checking effect substantially constant throughout a period of consecutive picks.

3. Mechanism as defined in claim 2, comprising parallel pivots for said plates, and resilient means spaced from said pivots tending to swing said plates on their pivots in opposite directions.

4. Mechanism as defined in claim 2, comprising parallel pivots for said plates, and resilient means disposed outwardly of said pivots tending to swing the inner ends of said plates away from each other.

5. In a loom having a lay and bracket means rigid therewith, two parallel pivots on said bracket means disposed in a plane transverse to the length of the lay, means for checking outward movement of a picker stick in response to a blow delivered to the picker head by the shuttle, which comprises a pair of plates mounted on said pivots, between which plates the stick travels and by which its motion may be dampened frictionally, automatic means responsive to the friction exerted by said plates upon the moving stick and acting upon the plates outwardly of said pivots for varying the spacing of said plates to maintain the checking effect substantially constant throughout a period of consecutive picks, and resilient means acting upon said pair of plates to hold them in line with the path of travel of the stick.

6. Mechanism as defined in claim 5, wherein said automatic means comprises two ratchets, one functioning during step by step rotation to spread the outer ends of said plates and the other functioning by its similar rotation to draw them together, and pawls responsive to the movements of said stick for rotating said ratchets.

7. Mechanism as defined in claim 6, wherein the pivots for said plates are yieldably mounted to permit limited movement inwardly, and wherein one of said pawls is attached to said bracket means and the other is reciprocable in said bracket means.

8. In a loom having a lay and bracket means rigid therewith, two parallel pivots on said bracket means disposed in a plane transverse to the length of the lay, means for checking outward

movement of the picker stick in response to a blow delivered to the picker head by the shuttle, which comprises a pair of plates mounted on said pivots, between which plates the stick travels and by which its motion may be dampened frictionally, automatic means responsive to the friction exerted by said plates upon the moving stick and acting upon the plates outwardly of said pivots for varying the spacing of said plates to maintain the checking effect substantially constant throughout a period of consecutive picks, said automatic means comprising a shaft extending crosswise of the outer ends of said plates, a ratchet pinned to said shaft between said plates, a second ratchet threaded upon said shaft between said first ratchet and the other of said plates, and pawls responsive to the movements of said stick for rotating said ratchets.

9. Mechanism as defined in claim 8, wherein the pivots for said plates are yieldably mounted to permit limited movement inwardly, and wherein one of said pawls is attached to said bracket means and the other is reciprocable in said bracket means.

10. In a loom having a lay and bracket means rigid therewith, two parallel pivots on said bracket means disposed in a plane transverse to the length of the lay, means for checking outward movement of a picker stick in response to a blow delivered to the picker head by the shuttle, which comprises a pair of plates mounted on said pivots, between which plates the stick travels and by which its motion may be dampened frictionally, automatic means responsive to the friction exerted by said plates on the moving stick and acting upon the plates outwardly of said pivots for varying the spacing of said plates to maintain the checking effect substantially constant throughout a period of consecutive picks,

30 11. Mechanism as defined in claim 10, wherein the pivots for said plates are yieldably mounted to permit limited movement inwardly, and wherein one of said pawls is attached to said bracket means and the other is reciprocable in said bracket means.

35 12. In a loom having a lay and bracket means rigid therewith, two parallel pivots on said bracket means disposed in a plane transverse to the length of the lay, means for checking outward movement of a picker stick in response to a blow delivered to the picker head by the shuttle, which comprises a pair of plates mounted on said pivots, between which plates the stick travels and by which its motion may be dampened frictionally, automatic means responsive to the friction exerted by said plates on the moving stick and acting upon the plates outwardly of said pivots for varying the spacing of said plates to maintain the checking effect substantially constant throughout a period of consecutive picks,

40 13. Mechanism as defined in claim 12, wherein the pivots for said plates are yieldably mounted to permit limited movement inwardly, and wherein one of said pawls is attached to said bracket means and the other is reciprocable in said bracket means.

45 14. In a loom having a lay and bracket means rigid therewith, two parallel pivots on said bracket means disposed in a plane transverse to the length of the lay, means for checking outward movement of a picker stick in response to a blow delivered to the picker head by the shuttle, which comprises a pair of plates mounted on said pivots, between which plates the stick travels and by which its motion may be dampened frictionally, automatic means responsive to the friction exerted by said plates on the moving stick and acting upon the plates outwardly of said pivots for varying the spacing of said plates to maintain the checking effect substantially constant throughout a period of consecutive picks,

50 15. Mechanism as defined in claim 14, wherein the pivots for said plates are yieldably mounted to permit limited movement inwardly, and wherein one of said pawls is attached to said bracket means and the other is reciprocable in said bracket means.

55 16. Mechanism as defined in claim 15, wherein the pivots for said plates are yieldably mounted to permit limited movement inwardly, and wherein one of said pawls is attached to said bracket means and the other is reciprocable in said bracket means.

60 17. Mechanism as defined in claim 16, wherein the pivots for said plates are yieldably mounted to permit limited movement inwardly, and wherein one of said pawls is attached to said bracket means and the other is reciprocable in said bracket means.

65 18. In a loom having a lay and bracket means rigid therewith, two parallel pivots on said bracket means disposed in a plane transverse to the length of the lay, means for checking outward movement of a picker stick in response to a blow delivered to the picker head by the shuttle, which comprises a pair of plates mounted on said pivots, between which plates the stick travels and by which its motion may be dampened frictionally, automatic means responsive to the friction exerted by said plates on the moving stick and acting upon the plates outwardly of said pivots for varying the spacing of said plates to maintain the checking effect substantially constant throughout a period of consecutive picks,

70 19. In a loom having a lay and bracket means rigid therewith, two parallel pivots on said bracket means disposed in a plane transverse to the length of the lay, means for checking outward movement of a picker stick in response to a blow delivered to the picker head by the shuttle, which comprises a pair of plates mounted on said pivots, between which plates the stick travels and by which its motion may be dampened frictionally, automatic means responsive to the friction exerted by said plates on the moving stick and acting upon the plates outwardly of said pivots for varying the spacing of said plates to maintain the checking effect substantially constant throughout a period of consecutive picks,

dampened frictionally, automatic means responsive to the friction exerted by said plates upon the moving stick for varying the spacing of said plates to maintain the checking effect substantially constant throughout a period of consecutive picks, a pair of parallel pivots upon which the plates are mounted intermediate their ends, and a second pair of pivots parallel to the first pair upon which the outer ends of the plates are mounted, said automatic means functioning to move said second pair of pivots transversely in opposite directions.

14. In a loom, means for checking outward movement of the picker stick in response to a blow, delivered to the picker head by the shuttle, which comprises a pair of plates between which the stick travels and by which its motion may be dampened frictionally, and automatic means responsive to variables in the load imposed upon the checking means for varying the spacing of said plates, whereby the checking effect upon the picker stick may be maintained substantially constant throughout a period of consecutive picks.

15. In a loom having a lay and bracket means rigid therewith, two parallel pivots on said bracket means disposed in a plane transverse to the length of the lay, means for checking outward movement of a picker stick in response to a blow delivered to the picker head by the shuttle, which comprises a pair of plates mounted on said pivots between which plates the stick travels and by which its motion may be dampened frictionally, and automatic means responsive to variables in the load imposed upon the checking means for varying the spacing of the plates, whereby the checking effect upon the picker stick may be maintained substantially constant throughout a period of consecutive picks.

16. In a loom, means for checking outward movement of the picker stick in response to a blow delivered to the picker head by the shuttle, which comprises a pair of plates between which the picker stick travels and by which its motion may be dampened frictionally, and means responsive to the degree of load imposed upon the

5 checking means during a given outward stroke of the picker stick for varying by a small increment the spacing of the plates during the next inward stroke of the picker stick for the purpose of maintaining the throw of the picker stick substantially uniform throughout a period of consecutive picks.

10 17. In a loom, means for checking outboard movement of the picker stick in response to a blow delivered to the picker head by the shuttle, which comprises a pair of plates between which the picker stick travels and by which its motion may be dampened frictionally, a pair of bodily movable parallel pivots upon which said plates are mounted to swing through a limited angle, and means for mounting said pivots to guide their movement away from each other as friction developed upon the inboard travel of the picker stick tends to move said plates in the inboard direction.

15 18. Mechanism as defined in claim 17, wherein said plates are mounted intermediate their ends upon a pair of parallel pivots and at their outer ends upon a second pair of pivots parallel to the first pair, means for moving said second pair of pivots transversely in opposite directions responsive to outboard travel of the picker stick for controlling the degree of friction between said plates and said picker stick, and means for 20 spreading said first pair of pivots responsive to the inboard travel of said picker stick for relieving friction on that stroke.
